IRONING MACHINE

William Neal Gallagher, Newton, Iowa

Application February 15, 1932, Serial No. 592,879

2 Claims.

(Cl. 68—9)

This invention relates to ironing machines and more particularly to the manual release means for the ironing shoe thereof.

One of the objects of the invention lies in the provision of a manual release mechanism for the ironing shoe of the roll type ironer, said mechanism including a manually controlled cam operating portion having the function not only of a safety release mechanism but also permitting, by manual operation, movement of the same to a steaming position, without the necessity of touching the shoe.

Another object lies in the provision of a manually controlled safety release connection between the ironing shoe and roll portion of an ironing machine, said mechanism including a manually controlled spring tensioned cam connection with the ironing shoe support, which permits initial quick release of the shoe and finally, by further movement of the manual control member, movement of the shoe to a horizontal position satisfactory for the steaming operation.

Other objects will appear in the following specification, taken in connection with the annexed drawing, in which—

Fig. 1 is an elevational view of applicant's manual release assembly for a roll type ironer; and

Fig. 2 is a similar view showing the mechanism in the released position and with the ironing shoe in the steaming position;

Fig. 3 is a view of the mechanism taken from line 3—3 in Fig. 1.

It will be noted that applicant has disclosed merely that portion of a well known type of ironing machine, in which it is believed novelty lies. In other words, the present application is directed solely to the manual release assembly of the well known roll type ironer.

Before referring specifically to the drawing, it might be well to state that the manual release assembly shown in the drawing is a well known portion of the conventional roll type ironer.

This type of ironer obviously includes a power driven roll shown generally in the drawing at 10, a heated ironing shoe 11, and various types of mechanism for synchronously driving and operating the above two main portions of the ironer.

In other words driving mechanism for the roll and shoe is provided, which permits rotation of the roll 10 and intermittent movement of the ironing shoe towards and from the roll by means of various kinds of driving connection.

The movement of the ironing shoe 11 towards

the roll is accomplished through movement of a lever not shown in the drawing, but nevertheless one of such well known type as to obviate description, in view of the fact that the present application is directed solely to the manual release mechanism now to be described.

A laterally disposed bar or shaft 12, conventional in construction is so arranged and driven by mechanism heretofore described as to move the supporting mechanism, later to be described, 10 and therefore the ironing shoe 11, away as well as towards the roll 10. This shaft obviously has an intermittent forward and backward movement.

In the drawing, a supporting member 13 is 15 shown fixedly pinned as at 14 to the before described intermittently operating bar 12. This member 13 is capable of a predetermined and prescribed movement towards and away from the roll 10.

In Fig. 1 it will be noted that member 13 is in its predetermined forward position with respect to the shoe, while in Fig. 2 the same member is shown in its predetermined rearward position. In other words, this member always describes a certain arc and has a certain degree of movement towards and from the shoe.

Pivotedly mounted upon the bar 12 is an ironing shoe supporting member 15. A tensioned relationship between the shoe supporting member 15 and the fixed support 13 is provided in the bolt 16, cap screw 17, coil spring 18, and, see Fig. 2, the bolt head 19. The tension connection between members 13 and 15 is accomplished by an angular member 30 pivotally supported on member 15 by means of bolt 20. The angular extension of member 30 is provided with an opening through which the bolt 16 passes in a sliding manner. Spring 18 is retained between bolt head 19 and the angular portion of member 30 whereby member 15 is urged toward member 13 in the manner indicated in Fig. 2.

The ironing shoe 11 has a rearwardly extending bracket 21 which is pivotally connected to the ironing shoe support 15, as may be clearly seen from either view of the drawing.

Disposed in an operative position and pivotally mounted on the same axis as the mounting of the bracket 21 and ironing shoe support 15 is a crank 22. This crank is actually a casting 50 having an indented cam portion 23 formed integrally therewith. Further, a manually controlled release handle 24 is either formed integrally with or secured in said casting 23. It will be noted also that the cam 23 is capable 55

of operative connection and engagement with the curved upper end 25 of the before mentioned support 13, which in turn is fixedly connected as at 14 to the intermittently movable bar 12.

With respect to the operation of applicant's quick hand release assembly, in Fig. 1, the various portions are disposed in their normal position. In other words, the release handle 24 has been moved to a forward position with the opposed cam 23 engaging the curved portion 25 in such manner as to hold the ironing shoe in a fixed position with respect to the stationary support 13 the spring 18 acting as described to retain cam 23 in abutment with portion 25.

It will be noted that movement of the support 13 induced by the intermittent rearward and forward movement of the bar 12 will merely cause the shoe to assume the ironing position shown in Fig. 1, or a rearward position somewhat away from the roll. However, irrespective of the movement of the shoe as above described, the release handle still maintains a fixed position, due to the connection between the cam portions 23 and 25.

It is apparent that when the handle is in its normal and fixed position with respect to support 13, the shoe supporting bracket 15 has moved forwardly and that tension has been created between said support and the member 13. However, should the operator desire to release the ironing shoe 11 from the roll 10 quickly and prior to any movement of control means, not shown, which would move the support 13 to a rearward position, he merely strikes the release lever 24 sharply in a rearward manner. This movement of the release lever obviously disengages the engaging surfaces 23 and 25 and automatically, due to this movement, as well as movement of the coil spring, the shoe is moved sharply away from the ironing roll.

Quick release mechanism of various types, although different from that herein shown, is used to release the ironing shoe suddenly in case of an accident of any character. However, in the present instance, applicant has so fashioned his quick release mechanism as to accomplish also another object. Upon viewing Fig. 2, it will be found that the operator has not only released the cam connection, which in turn quickly releases the ironing shoe, but that he has also moved the manual release lever such distance rearwardly as to move the ironing shoe to a horizontal position, such movement being finally induced by a portion 26 of the cam abutting and supporting the under side of the shoe 11. The ironing shoe, when held in this position, is now sufficiently removed and so positioned in a horizontal manner, as to be capable of use for a steaming operation.

It is thought apparent that applicant has provided not only a simple quick release mechanism, but also one capable of further operation to enable it to be used also for the purpose of moving

the ironing shoe to a steaming position, without touching the shoe with the hand.

Further, with respect to the operation of applicant's device, it is apparent that in order that the ironing shoe may again assume an operative position adjacent the ironing roll, the operator must first move the release handle 24 to a forward position, wherein the cam surfaces 23 and 25 will again be engaged. Thus, the ironing shoe is again held in a fixed position with respect to the support 13 and further, said shoe has assumed such position that forward movement of the support 13 will press the ironing shoe against the roll and vice versa.

What I claim is:

1. In a device of the class described, in combination, an ironing roll, an ironing shoe, a lever member having a predetermined movement towards and from the ironing roll, an ironing shoe support movable relative to said lever and roll, a connection between the lever and the ironing shoe, tensioning means connecting the lever and support adapted to urge the support toward the lever and away from the roll, a manually operated cam adapted to positively move the support and shoe relative to the lever in opposition to the tensioning means, the tensioning means adapted to co-operate with the cam in such a manner that when the cam is moved in one direction the shoe is positively moved toward the roll, whereas when the cam is moved in the opposite direction the tensioning means operates to move the shoe away from the roll.

2. A device of the class described having in combination an ironing roll, an ironing shoe, a shaft having predetermined rotational movement, a lever member affixed thereto, said rotational movement of the shaft being such as to bring about movement of the lever member toward and from the ironing roll, an ironing shoe support pivotally supported upon said shaft to move relative to the lever and roll, said ironing shoe being pivotally supported thereon, tensioning means connecting the lever and support to urge the support toward the lever and away from the roll, a cam member pivotally mounted upon the support member, manual means for operating the cam upon its pivot, the cam being co-operative with a portion of the lever member and of such conformity that when the cam is moved in one direction the support member and shoe are moved away from the lever and toward the roll in opposition to said tensioning means and when moved in the opposite direction the tensioning means is rendered effective to move the shoe away from the roll, a portion of the cam being co-operative with the shoe whereby when the last mentioned movement of the cam is continued the said portion engages the shoe to bring about pivotal movement thereof to move the shoe to horizontal position.
